US0D1030393S

(12) **United States Design Patent** (10) Patent No.: **US D1,030,393 S**
(45) Date of Patent: ** Jun. 11, 2024

(54) **COCKTAIL SHAKER**

(71) Applicant: **Huayong Wang**, Huizhou (CN)

(72) Inventor: **Huayong Wang**, Huizhou (CN)

(**) Term: **15 Years**

(21) Appl. No.: **29/863,992**

(22) Filed: **Dec. 26, 2022**

(30) **Foreign Application Priority Data**

Oct. 9, 2022 (CN) 202230661894.4

(51) **LOC (14) Cl.** **07-01**

(52) **U.S. Cl.**

USPC **D7/300.1**; D7/510

(58) **Field of Classification Search**

USPC D7/507, 509-511, 523, 524, 528, 530, D7/532, 533, 536, 534, 537, 543, 300.1, D7/300.2, 303, 600, 619.1, 391, 392.1, D7/396.1, 396.2, 629, 900; D9/503, 505, D9/435, 439, 531; D3/202

CPC A63F 2009/0058; A47G 19/2205; A47G 21/18; A47J 41/00; B65D 1/00
